CLAIM

The ornamental design for an apparatus for forming paper on a cylinder mold, substantially as shown.

DESCRIPTION

FIG. 1 is a rear, top and right side perspective view of an apparatus for forming paper on a cylinder mold showing our new design;

FIG. 2 is a front, top and left side perspective view;

FIG. 3 is a front and right side perspective view;

FIG. 4 is a top plan view; and

FIG. 5 is a rear and left side perspective view.
